UNITED STATES PATENT OFFICE.

J. MELLEDGE FLAGG, OF PROVIDENCE, RHODE ISLAND.

DESIGN FOR LADIES' TUCKED PAPER COLLARS.

Specification forming part of Design No. 2,334, dated June 12, 1866.

To all whom it may concern:

Be it known that I, J. MELLEDGE FLAGG, of Providence, in the county of Providence and State of Rhode Island, have originated and designed a new Pattern for Ladies' Paper Collars, of which the following is a full, clear, and exact description, reference being had to the accompanying drawings, making part of this specification.

The collar is made of paper, which may be enameled to represent starching, and is formed of a series of parallel elevations, *a*, to represent the tucks or folds, and a corresponding series of depressions, *b*, extending longitudinally the length of the collar; and extending throughout the length of the elevated or thicker portions, representing the tucks of the collars, are series of indentations or points, to

represent stitching. Lines of any desirable color may be made over the indentations, to represent stitches of thread of different colors.

Referring to the drawings, Figure 1 represents a view of the face of the collar, and Fig. 2 is a section of the collar.

What I claim as my invention, and desire to secure by Letters Patent, is—

The design or pattern for ladies' paper collars herein set forth.

In testimony whereof I have signed my name to this specification in the presence of two subscribing witnesses.

J. MELLEDGE FLAGG.

Witnesses:

BENJAMIN F. DUNN,
GEORGE B. BARROWS.
